(57) **CLAIM**

The ornamental design for a wireless power supply tattoo pen, as shown and described.

DESCRIPTION

FIG. 1 is a top perspective view of the wireless power supply tattoo pen showing my new design.

FIG. 2 is a front view of the wireless power supply tattoo pen.

FIG. 3 is a rear view of the wireless power supply tattoo pen.

FIG. 4 is a left side view of the wireless power supply tattoo pen.

FIG. 5 is a right side view of the wireless power supply tattoo pen.

FIG. 6 is a top view of the wireless power supply tattoo pen.

FIG. 7 is a bottom view of the wireless power supply tattoo pen; and,

FIG. 8 is a bottom perspective view of the wireless power supply tattoo pen.

Any shading and cross-hatching are not features of the design but are utilized to illustrate the surface contours of the wireless power supply tattoo pen design in the drawings.

1 Claim, 8 Drawing Sheets
